CLAIM

The ornamental design for a medicine tray, substantially as shown and described.

DESCRIPTION

FIG. 1 is a top perspective view of a medicine tray showing my new design;

FIG. 2 is a side elevational view taken approximately along the line 2—2 of FIG. 1;

FIG. 3 is a side elevational view taken approximately along the line 3—3 of FIG. 1;

FIG. 4 is a top plan view thereof; and

FIG. 5 is a bottom plan view thereof.

The sides opposite to those shown in FIGS. 2 and 3 are mirror images of the sides shown therein.
